UNITED STATES PATENT OFFICE.

HORACE H. BUGGIE, OF TOLEDO, OHIO, ASSIGNOR TO THE DURA COMPANY, OF TOLEDO, OHIO, A CORPORATION OF DELAWARE.

RUNWAY FOR GLASS.

Application filed June 19, 1920. Serial No. 390,244.

To all whom it may concern:

Be it known that I, HORACE H. BUGGIE, a citizen of the United States of America, residing at Toledo, in the county of Lucas and State of Ohio; have invented certain new and useful Improvements in Runways for Glass, of which the following is a specification, reference being had therein to the accompanying drawings.

10 This invention relates to runways for glass and has a particular application to the windows of automobiles or other vehicles, which commonly employ a vertically slideable glass plate.

15 It is the object of the present invention to provide a runway for a sliding window glass, which runway is formed of a strip of material that is yielding so as to readily conform to any irregularities in the thickness of

20 the glass, yet possesses sufficient firmness to provide a proper runway for the glass. I find that back check piano felt having a channel formed therein either during initial process of manufacture or sub-

25 sequently cut therein is highly advantageous for this purpose, and have hence illustrated the invention as employing such strip. The prevention of rattling of a sliding vehicle window glass in any of its positions of adjustment is a further object of the invention.

In the drawings:

Figure 1 is an interior view of a vehicle door having a sliding window of the type to which the invention is applicable;

Figure 2 is a sectional detail view taken on line 2—2 of Figure 1 and showing in cross section, the engagement of the glass with the runway;

Figure 3 is a fragmentary perspective view of the runway engaged by the glass.

In these views, the reference character A designates a vehicle door provided in its upper portion with a window opening B, which opening is fitted with a vertically slideable glass plate C. Said plate engages at its lateral edges in channels D, which are formed in the window frame portion E of the door A. Within each of the channels D, there is disposed a runway F, which may be advantageously formed of a rectangular

strip of felt, although like yieldable material could be employed. I have found that, for this purpose, a very desirable material is back check piano felt, having formed 55 therein either during the initial manufacture of the strip, or by subsequent cutting or machining process, a groove G wherein the lateral edges of the glass C may engage. By so forming the groove in the strip F, 60 none of the initial stiffness of the fibre is lost. A strip formed in the described manner is found highly advantageous, as compared with a strip which is folded to a channel form, one of its desirable effects be- 65

ing the establishment of a water proof seal between the glass and its frame. It will be

observed that the thickness of material pro- 70

vided at the bottom of the groove G is some- 75

what greater than that at each side of said groove, as this increases the firmness of the channel and assists in maintaining its shape. It is found that an increased durability results from use of a runway formed as

above described and that any binding ten- 80

dency between the runway and glass is sub- 85

stantially eliminated. Also the employment of the described runway facilitates assem- 90

bley, since no bending of the same is necessary prior to insertion thereof, in the channels D, 95

so that it may be very readily introduced into the channels without manipulation.

What I claim as my invention is:

1. A window runway comprising a strip of fibrous yieldable material, having a lon- 85

gitudinal channel therein for receiving the edge of a window glass, said channel being formed in the strip.

2. A window runway comprising a strip of back-check-piano felt, having a longitudinal 90

channel therein for receiving the edge of a window glass, said channel being formed in the strip.

3. A window runway comprising a strip of fibrous yieldable material having a longi- 95

tudinal channel therein for receiving the edge of a window glass, the thickness of said material at the bottom of said channel being greater than that at the sides of the channel, said channel being formed in the strip. 100

In testimony whereof I affix my signature.

HORACE H. BUGGIE.
